Primary Examiner — Ramzi S Almatrahi(74) *Attorney, Agent, or Firm* — Falk Ewers; Ewers IP Law PLLC(57) **CLAIM**

The ornamental design for a digital camera display, as shown and described.

DESCRIPTION

FIG. 1 is a top and rear perspective view of a digital camera display showing our new design; and,

FIG. 2 is a bottom and rear perspective view thereof.
 The broken lines depict portions of the digital camera display in which the design is embodied that form no part of the claimed design.**1 Claim, 2 Drawing Sheets**(56)
